UNITED STATES PATENT OFFICE.

DAN W. KELLOGG AND WILLIAM A. KIRBY, OF AUBURN, NEW YORK.

STEAM-BOILER.

SPECIFICATION forming part of Letters Patent No. 355,176, dated December 28, 1886.

Application filed December 21, 1885. Serial No. 186,294. (No model.)

To all whom it may concern:

Be it known that we, DAN W. KELLOGG and WILLIAM A. KIRBY, citizens of the United States, residing at Auburn, in the county of Cayuga and State of New York, have invented certain new and useful Improvements in Steam-Boilers, of which the following is a specification, reference being had therein to the accompanying drawing.

10 This invention has relation to steam-boilers for heating buildings; and for other purposes, containing a central magazine for coal; and the objects of our invention are to provide means for rapidly converting water into steam, and 15 superheating said steam and automatically controlling the air-supply.

Other objects and advantages of our invention will appear in the following description, and the novel feature thereof will be particularly pointed out in the claims.

The drawing represents a central vertical section of a steam-boiler constructed in accordance with our invention.

To a suitable annular base, A, forming the 25 ash-pit, to which access is had through a door, A', is arranged in any suitable manner the grate B, which may be shaken by the lever B'. The base is provided with an inwardly-projecting annular flange, A², upon which is 30 mounted the body of the steam-generator, consisting of an inner circular plate, C, and an outer concentric plate, C'. Said plates are connected at the bottom, either by flanging both plates outwardly and riveting their flanges together, or by other well-known means, and 35 they are connected at the top by flanging the inner plate outwardly against the outer plate and riveting them together, and thereby forming a narrow annular water-chamber, C², around 40 the fire-box of the generator. To the inner plate, C, a short distance above the grate B, are attached a series of brackets, D, to support a long coil, E, having its lower end suitably secured at e to the inner plate, C, and 45 connecting with its water-chamber, while its upper end is similarly connected at e' to said inner plate, and to reach the fastenings, so as to tighten them, hand-holes are formed opposite them in the outer plate, that are closed 50 by small cap-plates e². The long pipe E is coiled inwardly to form a horizontal coil, the inner end of which is bent on an ascending

spiral to form the inner coil, that is bent outwardly to form a horizontal coil above the first one, and when it has nearly reached the outer periphery of the first coil it is bent upward to form the outer end of the spiral coil, that is bent inwardly, as stated for the lower coil, and the operation is repeated until the desired number of coils is formed, the series 60 of coils being vertically staggered to cause the products of combustion to follow a zigzag course among them.

The upper or discharging end of the coil E is located above the level of the water in the 65 boiler, so that there is no interference with the escape of steam from said coil into the upper end or steam-chamber of the boiler. This arrangement of the coil is also described in a companion application filed by William A. 70 Kirby.

To increase the temperature of the steam received in the steam-chamber and superheat it on its way to the escape-pipe F, it is made to circulate through a large flat coil, F', secured at f to the inner shell of the boiler and communicating with its steam-chamber. Upon one side of the escape-pipe there is a branch pipe carrying a safety-valve, G, of usual construction.

The boiler proper is inclosed in a jacket, H, the upper end of which forms a smoke-chamber, out of which the products of combustion escape through the smoke-pipe H', in which is pivoted the damper H² to modify the direction of the draft.

To indicate the amount of water in the boiler and regulate the draft and its direction, there is inserted in the lower portion of the outer plate of the boiler a horizontal pipe, I, through 90 which the feed-water is admitted into the boiler. Upon the pipe I is mounted a vertical pipe, K, carrying a branch pipe, K', that is in communication with the steam-chamber of the boiler, and connected with the upper end of 95 the pipe K there is a diaphragm-valve, L, upon the central stem of which rests the horizontal lever M, pivoted at m to a standard projecting from the casing of the valve. Upon the lever M is placed a sliding weight, m², the position 100 of which regulates the amount of steam-pressure intended to be maintained before closing the draft entering at the ash-pit. For this purpose the opening in the ash-pit to remove

the ashes is closed by a door, A', hinged at the side to the base A, and hinged to the upper edge of the door A' is a smaller or draft door, N, having attached close to its lower edge and adjoining the hinges of the larger door A' a chain, N², the upper end of which is secured to the end of the lever M at a short distance from its pivot m, so that any elevation of the stem of the diaphragm-valve will have a tendency 10 to close the draft-door N. To reduce at the same time the updraft of the products of combustion to the smoke-pipe H', there is hinged to the side of the latter a pendent valve, N³, the lower edge of which is connected by a 15 chain, N⁴, to the opposite end of the lever M, from which the lower draft-chain, N², is pendent, so that while the bottom draft-door, N', becomes closed the upper valve or draft-door, N³, becomes open. To the side of the pipe K, 20 at a point coinciding with the top of the water in the boiler, is secured a glass gage, P, of ordinary construction.

Within the center of the boiler is placed the magazine Q. Its upper end is provided with 25 a cap, Q', having its lower edge resting upon the top of the boiler and its upper edge turned inwardly, and upon the latter is placed the cover Q², and adjacent thereto projects upwardly a pipe, Q³, to carry any gas that may 30 be formed in the magazine. Centrally under the lower end of the magazine there is secured upon the grate-bars of the grate B a hollow cone, R, formed independently of said grate, and having fine perforations r therethrough 35 to admit air within the mass of coal usually collected on the grate directly under the magazine, keep the grate comparatively cool at that point, and at the same time deflecting the coal toward the side of the boiler, where it is most 40 needed to heat the body of the boiler and the coil E, placed therein.

Having now fully described our invention, we claim—

1. The combination of the concentric inner and outer shells of the boiler and its central 45 magazine with a water-pipe surrounding said magazine, and having its lower end attached to the boiler substantially opposite the lower end of the magazine, and first coiled inwardly toward the magazine, followed by another coil 50 extending outwardly, the series of coils being staggered one above the other, substantially as and for the purpose described.

2. The combination of the concentric inner and outer shells of the boiler and the water- 55 coil within having its lower end connected with the body of the boiler at a point substantially on a level with the lower end of the magazine, and its upper coil above the water-line in the boiler, with a superheater located 60 above said upper coil, and a magazine in the center of the coil, substantially as described.

3. The combination of the inner and outer shell of the boiler, its coil and jacket, and a smoke-pipe issuing vertically from said jacket, 65 with a magazine provided with a cap resting thereon, said cap having its upper edge turned inwardly, and a pipe projecting upward from the upper bend thereof, substantially as and for the purpose described.

4. The combination of the inner and outer shell of the boiler, its coil and magazine within 70 said coil, with the jacket H, smoke-pipe H', projecting vertically from said jacket, and pendent valve N³, hinged to said smoke-pipe, 75 substantially as and for the purpose described.

In testimony whereof we affix our signatures in presence of two witnesses.

DAN W. KELLOGG.
WILLIAM A. KIRBY.
